CONVERTIBLE CHAIR-BED

Martin Jager and Julius Gombar, New York, N. Y.

Application January 17, 1934, Serial No. 706,912

5 Claims. (Cl. 5—41)

This invention relates to new and useful improvements in a convertible chair bed.

The invention has for an object the construction of an article as mentioned which is characterized by a seat and extension with a hinged back arranged to maintain a raised or a lowered position, and mechanism for extending the seat extension to provide sufficient length so that the chair may be used as a bed.

10 Still further the invention proposes an arrangement whereby a catch is adapted for holding the back in an upright position and releasable to allow the back to be moved to the horizontal position.

15 Furthermore the invention also proposes the provision of means for holding the back in a substantially horizontal position when lowered.

20 As another object of this invention it is proposed to arrange a carriage beneath the seat supporting the seat extension piece adapted to be raised to a suitable height when the carriage is extended so as to add to the length of the device.

25 Still further the invention proposes the construction of an article as mentioned which is simple and durable and which may be manufactured and sold at a reasonable cost.

30 For further comprehension of the invention, and of the objects and advantages thereof, reference will be had to the following description and accompanying drawings, and to the appended claims in which the various novel features of the invention are more particularly set forth.

35 In the accompanying drawings forming a material part of this disclosure:

Fig. 1 is a side elevational view of a convertible chair bed constructed according to this invention.

40 Fig. 2 is an elevational view looking from the left in Fig. 1.

Fig. 3 is an elevational view looking from the right in Fig. 1.

Fig. 4 is a plan view of the carriage and a portion of the seat extension piece, per se.

45 Fig. 5 is a vertical sectional view taken on the line 5—5 of Fig. 4.

Fig. 6 is a vertical sectional view taken on the line 6—6 of Fig. 4.

50 Fig. 7 is a transverse vertical sectional view taken on the line 7—7 of Fig. 4, a portion of the chair being also shown.

Fig. 8 is a fragmentary enlarged detailed view of a portion of Fig. 5.

55 Fig. 9 is a transverse vertical sectional view taken on the line 9—9 of Fig. 3.

Fig. 10 is a fragmentary vertical sectional view taken on the line 10—10 of Fig. 7.

Fig. 11 is a fragmentary vertical sectional view taken on the line 11—11 of Fig. 4.

Fig. 12 is a fragmentary enlarged horizontal sectional view taken on the line 12—12 of Fig. 6.

Fig. 13 is a fragmentary enlarged sectional view as though taken on the line 13—13 of Fig. 4 but showing the parts in slightly different position.

Fig. 14 is a sectional view taken on the line 14—14 of Fig. 13.

The convertible chair bed according to this invention comprises a seat 10 supported upon a pair of vertical side walls 11 producing an empty space beneath the seat. A seat back 12 is hingedly associated with the seat 10 and is adapted to maintain an upright position as illustrated in Fig. 1 or be lowered into a horizontal position as indicated by the dot and dash lines in Fig. 1.

More particularly the rear edges of the walls 11 are provided with members 13 upon which the seat back 12 is hingedly connected by the pivotal rod 14. This seat back 12 has a protruding portion 15 arranged to the front of the pivot 14 and provided with a projecting hook 16 adapted to engage a transverse bar 17 between the side walls 11 so as to limit downward pivoting of the seat back to the horizontal position indicated by the dot and dash lines. Coil springs 14' on rod 14 tend to keep the seat back in vertical normal position.

A catch is provided for holding the back upright. This catch comprises a rod 18 which is slidable vertically in the back 12 and has a top head 19 accessible through an opening 20 in the back side of the seat back 12. A pair of oppositely directed links 21 pivotally connect the rod 18 with levers 22 which are pivotally connected intermediately upon standards 23. The lower ends of the levers 22 pivotally connect with keeper members 25 adapted to engage into openings formed in members 12 and 13. Springs 25' are arranged upon the keepers 25 and have their ends connected between the levers 22 and the seat back 12 and normally serve to urge the keepers outwards into the latched positions. The arrangement is such that the handle 19 may be lifted to move the rod 18 upwards to move the links 21 so as to pivot the levers 22 and draw the keepers 25 inwards to disengage from the members 13. Then the seat back may be lowered as previously described.

A carriage 26 is arranged below the seat 10 and supports a seat front extension 27 adapted when the carriage is extended, to itself assume a raised

40 position.

45 Fig. 4 shows the carriage 26 in its normal position below the seat 10 and the carriage 26 is shown in its raised position.

50 Fig. 9 shows the carriage 26 in its raised position.

position level with the seat 10 and so extend the size of the bed. The carriage 26 comprises four vertical walls simulating the sides of a box joined by several longitudinal members 28 at the bottom 5 and at the top. A means is provided for extending the carriage and comprises a spring of several leaves 29 acting against the rear wall of the carriage and a transverse bar 30 between the side walls 11. The carriage 26 is provided at the sides 10 with wall extensions 32. Several rollers 33 are arranged upon the outer faces of the wall extensions 32 and on the side walls of the carriage and work in tracks 34 mounted upon the inner faces of the walls 11. Several rollers 35 are mounted 15 on the carriage 26 and rest upon the ground serving to aid in supporting the carriage.

The carriage 26 is shown in its retracted position in Fig. 1. It should be noticed that in this figure all of the rollers 33 engage the tracks 34. 20 When the carriage is extended, necessarily the rollers 33 upon the front of the carriage will extend out from the tracks, but the rear rollers 33 in conjunction with the rollers 35 are depended upon to slidably guide the carriage so that it may 25 easily be moved inwards.

The seat front extension piece 27 preferably should be an upholstered member mounted within a frame 37. This frame 37 has several longitudinal members 38 along its bottom. Several 30 bolts 39 extend through certain of the flanges 38 and are equipped with bottom nuts 40 serving to limit possible raising of the frame 37. These bolts 40 are adapted to engage against the top flanges 28 upon the carriage.

35 A means is provided for raising the seat front extension piece 27 from the carriage 26 to the level of the seat 10 and comprises several leaf springs 41 supported upon standards 42 projecting from the members 28 of the carriage 26.

40 These springs 41 engage against the undersides of certain of the flanges 38 and tend to normally urge the frame 37 upwards. The frame is restrained from rising by a rod 43 which is attached upon the center flange 38 and which engages into 45 a tubular member 44 mounted upon the bottom flange 28 of the carriage 26. A helical spring 41' is mounted upon the tubular member 44 and acts between a flange at the base of the tubular member and a flange upon the upper end of the rod 43 for the purpose of supplementing the action 50 of the springs 41 in lifting the seat extension piece 27. A lock rod 45 passes through the member 28 and engages a cutout in the rod 43 so as to hold the rod in lowered position. The lock rod 45 is urged into locking position by a spring 46 which is attached at one end upon a lug 45' of the lock rod and at the other end on the carriage 26. A cross piece 47 is mounted upon the lug 45' and extends from the sides of the carriage 26 and is 55 adapted to strike against stationary stop members 48 fixed upon the sides of the walls 11 located so as to cause the releasing of the rod 43 when the carriage is in its fully extended position.

60 A means is provided for holding the carriage 65 26 retracted and comprises a hook 49 fixed on a rod 49' supported on the side walls 11 and engageable in an opening 28' of one of the members 28. Springs 57 on the rod 49' act between the rod 49' and the walls 11 for normally urging the hook 49 into latching position. The hook 49 has a rear cam shaped projection 49a on its rear end adapted to be engaged upon the hook 16 for the purpose of pivoting the hook 49 to disengage it from its latching position.

75 A mechanism is also provided for latching the

seat back 12 in its lowered position. This mechanism comprises a rod 50 having a bolt 51 fixed at its top end and working in a slot 18' in the rod 18. The rod 50 slidably passes through a block 51a fixed within the seat back 12. A spring 52 acts between the block 51a and a head 50' upon the end of the rod 50 for normally urging the rod 50 outwards. The head 50' is formed with an elongated slot 50a through which the rod 14 passes. The head 50' also engages against a bar 10 53 mounted between the members 13. The arrangement is such that when the seat back 12 is pivoted into the horizontal position illustrated by the dot and dash lines in Figs. 1 and 9, the bar 50 will be urged inwards by an arcuate shape on the 15 top of the bar 53 and then outwards as illustrated by the dot and dash lines in Fig. 9, to assume a position over the top of the bar 53 and so latch the seat back in the horizontal position. Because of the slot 18' the bar 18 may be moved to free 20 the keeper members 25 without transmitting any motion to the bar 50. The seat back may be raised from the horizontal position by pulling the head 19 of the bar 18 so as to efficiently move the bar to cause the end of the slot 18' to strike 25 against the bolt 51' and move the bar 51 so that the head 50' of the bar disengages from its position over the top of the bar 53 freeing the seat back so that it may be raised.

In Fig. 1 the seat front extension piece 27 is 30 shown in dot and dash lines in its raised position. A means is provided for holding this seat piece 27 in the raised operative position and comprises slide bars 60 slidably supported beneath certain of the flanges 38 and formed with cutouts through which bolts 61 pass. These bolts have heads 62 at the upper ends resting upon the flanges 38. At the lower ends the bolts 61 are provided with cutout 63 adapted to be engaged by the slide bars 60 so as to latch the bolts 40 61 against upward or downward motion. These bolts 61 are soldered, riveted, or welded to the flanges 38 so as to act in unison with the flanges. Springs 64 act between the slide rods 60 and stationary pins 65 projecting from the flanges 38 45 so as to formally urge the slide bars 60 rearwards into their operating positions. A mechanism is provided whereby the slide bars 60 may be moved forwards for releasing the bolts 61.

The mechanism mentioned at the latter portion of the previous paragraph comprises a finger 66 engaging each of the slide bars 60 and projecting from a transverse shaft 67 swiveled in the sides of the carriage 26. Another finger 68 projects from the shaft 67 and connects with a vertical rod 69 terminating at the bottom end with a horizontal portion 70. A slide 71 is supported upon the horizontal portion 70 and extends from the front of the carriage 26. This slide 71 is formed with an elongated slot 72 through which a rivet 73 from the horizontal portion 70 extends. The slide 71 may be pulled out as allowed by the slot 72 and then a person may step upon the extended slide for the purpose of moving the rod 69 downward to pivot the shaft 67 and cause the finger 66 to move the slide bars 60 and so free the bolts 61. The slide bars 60 are of channel shape, see Fig. 7 and the openings for coaction with the openings 63 are formed in the base of these channel shapes. Any arrangement may be used for slidably supporting the slide bars 60 in position for example brackets 75.

The operation of the device may be summarized as follows: Assume it to be in the position 75

illustrated in full lines in Fig. 1. The device may now be used as a chair. To convert it into a bed it is necessary that one's fingers be engaged through the opening 20 and move the head 19 and rod 18 upwards. This causes the release of the keepers 25 so that the back 12 may be pivoted to the horizontal position. During the motion of the seat back 12 to the horizontal position the hook 16 will strike the cam end 49^a of the hook 49 to pivot the hook 49 out of its latching position. This releases the carriage 26 which is immediately urged outwards by the spring 29. When the carriage has substantially reached its fully extended position the cross piece 47 will strike the stop members 48 to arrest the motion of the lug 45' while the carriage itself may move slightly further outwards until arrested by compression of the spring 46. The relative rearward motion of the lug 45' moves the rod 45 so that it disengages from the rod 43 releasing the seat extension piece 27 which is then immediately raised by the springs 41 and 41'.

The nuts 40 will strike certain of the flanges 28, see Fig. 11, to limit the upward motion of the extension 27. Simultaneously the cutout portions of the rods 61 will be aligned with the openings in the channel shaped slides 60 so that the springs 64 may move within the channel shaped slides 60 to latch the seat extension in the raised position. The device may now be used as a bed.

The device may be converted to the chair, by first raising the seat back 12 from the horizontal to the vertical condition. As this seat back is raised the hook 16 will strike the cam 49^a and idle past without any effect, except momentarily pivoting of the hook 49 which is then immediately returned by the springs 57. Next the slide 71 should be moved outwards and stepped upon to cause downward motion of the rods 69 and 40 pivoting of the finger 68, turning of the shaft 67, and moving the fingers 66 and the channel shaped slide bars 60 into positions in which the bolts 61 are free. Then the seat front piece 27 should be depressed manually until the rod 43 is completely extended in the tubular member 44. Next the carriage 26 should be moved inwards and this automatically causes the transverse rod 47 to leave the stops 48 so that the spring 46 may move the catch rod 45 to latch the rod 43 in the lowered position. Thus the carriage 26 is now latched in its lowered position. The carriage 26 must be moved completely inwards against the action of the spring 29 until the hook 49 engages the opening in the member 28 and holds the carriage in the retracted position.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new and desire to secure by United States Letters Patent is:—

1. A convertible chair bed, comprising a seat, a back hinged on said seat, a catch for holding said back upright, means for holding said back lowered to a horizontal position, a carriage below said seat supporting a seat front extension piece, means for extending said carriage to the front of said seat, means for causing said seat front extension piece to move from the carriage to the level of said seat, means for releasably holding said carriage retracted, and means for holding said

front extension piece in a lowered position, comprising a rod from said extension piece slidably engaging a vertical tubular member fixed upon said carriage, a latching rod engaging said rod, and means for moving said latching rod as the carriage assumes its fully extended position. 5

2. A convertible chair bed, comprising a seat, a back hinged on said seat, a catch for holding said back upright, means for holding said back lowered to a horizontal position, a carriage below 10 said seat supporting a seat front extension piece, means for holding said carriage and automatically operable for extending said carriage to the front of said seat when said back is lowered, means automatically operable for holding said 15 seat front extension piece and for causing said seat front extension piece to move from the carriage to the level of said seat when said carriage reaches its extended position, and means for releasably holding said seat front extension piece 20 in its raised position.

3. A convertible chair bed, comprising a seat, a back hinged on said seat, a catch for holding said back upright, means for holding said back lowered to a horizontal position, a carriage below 25 said seat supporting a seat front extension piece, means for holding said carriage and automatically operable for extending said carriage to the front of said seat when said back is lowered, means automatically operable for holding said 30 seat front extension piece and for causing said seat front extension piece to move from the carriage to the level of said seat when said carriage reaches its extended position, and means for releasably holding said seat front extension piece 35 in its raised position, comprising bolts rigidly connected with the seat front extension piece and extending downwards and formed with cutouts near the lower ends, slides mounted upon said carriage and formed with openings through 40 which said bolts extend and adapted to assume positions to engage the cutouts in the bolts for holding the bolts in raised positions, and means for moving said slides to free the bolts.

4. A convertible chair bed, comprising a seat, a back hinged on said seat, a catch for holding said back upright, means for holding said back lowered to a horizontal position, a carriage below 45 said seat supporting a seat front extension piece, means for holding said carriage and automatically operable for extending said carriage to the front of said seat when said back is lowered, means automatically operable for holding said 50 seat front extension piece and for causing said seat front extension piece to move from the carriage to the level of said seat when said carriage reaches its extended position, and means for releasably holding said seat front extension piece 55 in its raised position, comprising bolts rigidly attached on said seat front extension piece and extending downwards and formed with cutouts, slides mounted upon said carriage and formed with openings through which said bolts extend and engageable with said cutouts to hold the bolts in raised positions, a shaft rotatively supported on the carriage, fingers mounted upon said shaft and engaging said slides for moving the slides to free the bolts when the shaft is turned, another finger mounted upon said shaft, a rod connected with the latter finger, and an 60 extendable slide connected with said rod. 65

5. A convertible chair bed, comprising a seat, a back hinged on said seat, a catch for holding said back upright, means for holding said back lowered to a horizontal position, a carriage below 70 75

said seat supporting a seat front extension piece, means for holding said carriage and automatically operable for extending said carriage to the front of said seat when said back is lowered, means automatically operable for holding said seat front extension piece and for causing said seat front extension piece to move from the carriage to the level of said seat when said carriage reaches its extended position, and means for releasably holding said seat front extension piece

in its raised position, said means for holding the carriage including a member from said carriage engaging a stationary latch, said stationary latch including a pivotal member engaging said member and having a tail piece, and an element from said seat back engageable against said tail piece as the seat back is moved from the upright to the horizontal position to release the latch.

MARTIN JAGER.
JULIUS GOMBAR. 10
